Primary Examiner — Michael A. Pratt*Assistant Examiner* — Adam C Mager(74) *Attorney, Agent, or Firm* — Barnes & Thornburg LLP(57) **CLAIM**

We claim the ornamental design for a cargo restraint strap, as shown and described.

DESCRIPTION

FIG. 1 is a front perspective view of a cargo restraint strap in accordance with our new design;

FIG. 2 is a front elevation view of the cargo restraint strap of FIG. 1;

FIG. 3 is an enlarged view of the cargo restraint strap of FIG. 2;

FIG. 4 is a rear elevation view of the cargo restraint strap of FIG. 1;

FIG. 5 is a right-side elevation view of the cargo restraint strap of FIG. 1;

FIG. 6 is a left-side elevation view of the cargo restraint strap of FIG. 1;

FIG. 7 is a top plan view of the cargo restraint strap of FIG. 1; and,

FIG. 8 is a bottom plan view of the cargo restraint strap of FIG. 1.

The broken lines depict portions of the cargo restraint strap that form no part of the claimed design.
